UNITED STATES PATENT OFFICE.

LOUIS BRAUER, OF WASHINGTON, DISTRICT OF COLUMBIA, ASSIGNOR TO HIMSELF, L. G. BRANDEBURY, AND JOS. B. STEWART, OF SAME PLACE.

IMPROVED APPARATUS FOR PAYING OUT TELEGRAPHIC CABLES.

Specification forming part of Letters Patent No. 19,278, dated February 2, 1858.

To all whom it may concern:

Be it known that I, LOUIS BRAUER, of Washington, in the District of Columbia, have invented a new and useful Apparatus to be Applied to Steamers for Paying out Telegraph-Cable; and I do hereby declare that the following is a full, clear, and exact description of the same, reference being had to the accompanying drawings, forming part of this specification, in which—

Figure 1 is a plan or top view of a steamer with my apparatus applied to it. Fig. 2 is a vertical longitudinal section of the same.

Similar letters of reference in each of the several figures indicate corresponding parts.

This invention is designed to overcome the difficulty which has heretofore attended the laying of telegraph-cable across the ocean, said difficulty being the breaking of the cable by undue strain resulting from the incapability of the paying-out apparatus to pay out the cable as rapidly or in the same ratio as the speed of the steamer may be increased by a change in the pressure of steam or action of the current or wind.

The nature of my invention consists in the arrangement of the spring-pulley frame with the paying-out apparatus and the valves of both paying-out engine and the propelling-engine, or with either of the same separately, whereby a yielding support is provided to support and weigh the cable, and also as soon as the speed of the steamer increases so as to endanger the cable the valves of the paying-out engine are operated so as to increase the supply of steam to the paying-out engine, or the valves of the propelling-engine with paying-out engine operated so as to so decrease the supply of steam to said engine, and thus the paying out of the cable increased sufficiently to compensate for the increased speed acquired by the steamer, or the speed of the steamer reduced sufficiently to avoid strain and breakage of the cable.

To enable others skilled in the art to make and use my invention, I will proceed to describe its construction and operation.

A represents a steamer of ordinary or any other approved construction; B, the propelling-engine.

C C represent the straight grooved paying-

out cylinders, arranged on the second deck near the stern of the steamer, and geared together by wheels D D.

E E represent the engine for driving these cylinders. This engine has two cylinders and two pistons, one of which latter is connected by ordinary eccentrics to each end of one of the paying-out cylinders, so that the motion of said cylinders shall be changed suddenly from fast to slow, and vice versa, as occasion may require, without any loss of time, as would be the case if a single cylinder and balance-wheel were used. The steam-cylinders E E are furnished with ordinary steam-chests and slide-valves, and steam is supplied to said chests by means of a connecting-pipe, F, which connects with the supply-pipe G of the boiler, being furnished at the connection with a cut-off valve or cock, H, similar to the cut-off valve or cock I of the propelling-engine. These cocks are arranged just the reverse of each other, so that one gradually cuts off while the other increases the supply.

J represents the pulley-frame for supporting and guiding the cable as it passes from the grooved cylinders. This frame is pivoted to the upper edge of the steamer's stern, so as to be capable of turning on its axis from a perpendicular to a horizontal or other position as the strain comes upon the cable from increase in the speed of the steamer, and thus relieve the cable and effect the supply of the steam to the paying-out engine and the cut-off of the same from the propelling-engine, as occasion may require. It is also prevented from descending suddenly and rendered self-adjusting by means of springs a a, coiled round its axis and secured to the same by one of its ends and to it by the other. The legs b b of said frame are also prevented from rising suddenly, and yet made capable of rising gradually, and then of readjusting themselves with the frame by means of an auxiliary spring, c. On the axis of this frame a guide-pulley, d, is fixed, and on the cross-head of the same three tension guide-pulleys, e f g, are arranged so as to be capable of sliding laterally, and thus accommodate themselves to the motion of the vessel and avoid strain on the cable when the steamer pitches and rocks in a storm.

O represents an index-dial arranged along

side the frame. This dial, in connection with one of the standards of the frame, will indicate the weight or strain upon the cable.

K represents a connecting-rod leading from the automatic regulating-frame to the cut-off valve or cock H of the paying-out engine, and from said valve or cock H to an elbow-lever, h, and then down to the cut-off valve or cock I of the propelling-engine.

L represents the telegraph-cable. It is passed through a guide, i, and then carried several times round the grooved paying-out cylinders, being crossed each time it is carried round, and made to lie snugly in the grooves of said cylinder, as shown in Figs. 1 and 2, and after being thus arranged it is carried under the pulley d of the regulating-frame, and up by the pulley e over the pulley f, and down by the pulley g, and from thence let down into the ocean, as illustrated in the drawings.

With this invention it may be evident that all possibility of the cable being strained gradually or suddenly is avoided by employing the pivoted turning spring-frame, as said frame

serves to receive any sudden shock, and thus relieve the cable, or in case of change of speed of the vessel taking place, so as to endanger the cable, it yields under said strain, and thereby draws upon the connecting-rod K and lets on more steam to the paying-out engine, and partially cuts off the supply to the propelling-engine. The effect is just the reverse, or such as to insure a perfect operation, when the paying out of the cable becomes more rapid than is required to meet the demands of the speed of the steamer, as all the parts are made self-adjusting by means of springs and weights.

What I claim as my invention, and desire to secure by Letters Patent, is—

The arrangement of the spring pulley-frame with the paying-out apparatus and the valves of both the paying-out engine and propelling-engine, or either of the same separately, substantially as and for the purposes set forth.

LOUIS BRAUER.
